SEPARABLE SNAP FASTENER SOCKET

Moses F. Carr, Lincoln, Mass., assignor to United-Carr Fastener Corporation, Cambridge, Mass., a corporation of Massachusetts

Application January 17, 1933, Serial No. 652,157

2 Claims. (Cl. 24—77)

My invention aims to provide improvements in separable snap fastener sockets.

In the drawing which illustrates preferred embodiments of my invention:

5 Figure 1 is a plan view of a strap installation showing one use of a socket made according to my invention;

Fig. 2 is an enlarged section taken on the line 2—2 of Figure 1;

10 Fig. 3 is a plan view of a blank from which is formed a socket like that shown in Figs. 1 and 2;

Fig. 4 is a plan view of the socket shown in Figure 1 prior to attachment to a strap;

15 Fig. 5 is a plan view of a blank showing a modified form of socket which is attached by means of integral prongs;

Fig. 6 is a side elevation of a socket formed from the blank shown in Fig. 5; and

20 Fig. 7 is a section of a socket installation showing the manner in which the socket shown in Fig. 6 is attached to a carpet or the like.

My improved socket, as illustrated by the annexed drawing, is preferably formed from a single piece of metal and is adapted to be used 25 in various fastener installations. As examples of the variety of ways in which my improved socket may be used I have illustrated in Figs. 1 through 4 a socket for slidable attachment to a strap or the like and for attachment to a carpet or other like installations, as illustrated in Figs. 5 through 7. In each of the two types of socket illustrated the only difference resides in the means for attachment.

Referring now to the particular socket illustrated in Figs. 1 through 4, there is shown a slide fastener socket formed from a single piece of sheet metal and having a base 1, oppositely spaced strap-receiving slots 2—2 and a pair of yieldable arms 3—3 located between the said strap-receiving slots. The yieldable arms 3—3 are preferably twisted out of the plane of the base 1 (Fig. 2) so that they provide an elongated stud-receiving aperture 4 therebetween for reception of the stud 5 attached to the other end 45 of the strap 6 which passes through the strap-receiving slots 2—2, as best illustrated in Figs. 1 and 2.

The socket just described is preferably formed from a flat, thin blank of metal which is cut out in the form shown in Fig. 3 prior to bending and forming the yieldable arms 3—3 into the shape illustrated in Fig. 4. Thus it is only necessary to provide a thin slit (Fig. 3) in the material between the slots 2—2 to form the stud-receiving aperture 4. The aperture 4 is made into the

proper size for receiving the stud 5 when the arms 3—3 are twisted into their ultimate shape. Therefore a much smaller blank can be used than would be necessary if the stud-receiving aperture were made full size in the first blanking 5 operation.

Aside from economy from a manufacturing standpoint, the twisted arms 3—3 are particularly desirable because they yield laterally relative to each other in a sort of torsional twisting 10 action to permit entrance of the head of a stud therebetween. While the arms, because of their relation to the base, may yield torsionally quite readily, they resist to a large extent any tendency to yield toward and away from the base when 15 the stud is entered into or removed from the stud-receiving aperture. The socket is, therefore, strong and durable even though very simple in construction because it has a more lasting resiliency in the arms than similar sockets 20 having the arms located substantially in the plane of the base. Furthermore, even though the arms of applicant's socket are twisted out of the plane of the base they cannot become readily crushed in the normal use of the socket. 25

Referring now to the particular socket structure illustrated in Figs. 5 through 7, I have shown one which is adapted to be attached to structures other than straps and the like. In Fig. 7 I have illustrated the socket as being attached to a relatively thin carrying medium 8 by means of attaching prongs 9 formed integral with the socket. Aside from the prongs 9 the socket is the same in construction and operation as that illustrated and described in connection 30 with Figs. 1 through 4.

The socket illustrated in Figs. 5 through 7 is formed from the same sized blank as that illustrated in Fig. 3, because the prongs (Fig. 5) are formed from the material cut out to form the 40 slots 2—2 in the socket illustrated in Figs. 1 through 4. In the particular socket illustrated four prongs are formed and bent at right angles to the base from the ends of the slots 2—2 so that when the socket is attached to a carrying medium 45 the prongs may be bent curvilinearly downwardly into embedded relation with the carry medium, as illustrated in Fig. 7.

While I have illustrated and described preferred embodiments of my invention, I do not 50 wish to be limited thereby, because the scope of my invention is best defined by the following claims.

I claim:

1. A snap fastener socket having a base, a pair 55

of yieldable arms having both their ends connected to said base and being twisted to an angle of less than ninety degrees relative to the plane of said base and said arms having free outer edges and being spaced apart along their inner edges to provide a stud-receiving aperture between them and a slot between each of the arms and the base to permit a torsional action of said arms throughout their length for yielding action away from each other to permit enlargement of the stud-receiving aperture when a stud is forced between the arms, and attaching prongs formed integral with said base and extending therefrom in the opposite direction from the yieldable arms.

2. A fastener socket formed from a single piece of sheet metal and having a base portion, a pair

of yieldable arms having both their ends connected to said base portion and being twisted to an angle of less than 90° relative to the plane of said base portion, said arms having free outer edges and being spaced apart along their inner edges to provide a stud-receiving aperture between them, which aperture is larger in width adjacent to the middle of the arms than adjacent to where the arms join the base portion for reception of a fastener stud by a direct movement of the socket toward the stud, and said socket having oppositely positioned slots each of which is between an arm and the base portion to permit torsional action of said arms for enlargement of the stud-receiving aperture particularly adjacent to the widest portion.

MOSES F. CARR.
